METHOD OF COATING CANS

John M. Hothersall, Brooklyn, N. Y., assignor to
 American Can Company, New York, N. Y., a
 corporation of New Jersey

Application August 2, 1934, Serial No. 738,153

6 Claims. (Cl. 91—68)

The present invention relates to a method of coating cans and is particularly directed to the flowing of liquid coating material into and out of the cans being coated so that a coating deposit is left on their interior walls.

The present invention has as an object the provision of a method of coating cans by employing the can interior as a part of a coating chamber and causing the coating material to flow into the chamber so formed and over the desired interior surface of the can.

Another object of the invention is the provision of a method of coating cans which comprises momentarily sealing an open end of a can above a source of supply of liquid coating material and withdrawing air from the interior of the sealed can so that the coating material is raised from the source of supply and is caused to flow over the interior can surfaces, the excess of coating material being then returned to the source of supply leaving the interior can walls coated.

A further object of the invention is the provision of a method of liquid coating cans by creating a difference of pressure between the interior of the cans being coated and a source of liquid coating material so that the latter is caused to flow onto the interior surface of the can.

A still further object is the provision of a method of coating cans with a liquid coating material by closing the can to confine an interior space therein into which the liquid coating material is first introduced and then withdrawn by changing the difference of air pressure between the can interior and the source of coating material.

Numerous other objects and advantages of the invention will be apparent as it is better understood from the following description, which, taken in connection with the accompanying drawings, discloses a preferred embodiment thereof.

Referring to the drawings:

Figures 1 and 2 are sectional views of one form of apparatus for carrying out the method steps of the instant invention, Fig. 1 showing a can in position in the apparatus prior to coating, while Fig. 2 shows the apparatus and can during one of the coating steps; and

Figs. 3 and 4 are similar sectional views of a modified form of coating apparatus which also utilizes the inventive method.

In the method steps of the instant invention either cans having a bottom end or can bodies without ends are momentarily sealed in position on a supporting member associated with an open tank which may contain a supply of liquid coat-

ing material. In the description and claims that follow when the word "can" is used it will be understood to refer to either cans having a bottom and/or to can bodies without any ends.

In the sealed position of the can on its tank support the interior of the can is employed as a part of a coating chamber which cooperates with other parts of the supporting member to provide a closed communication between the can interior and the coating material in the tank. A difference of air pressure is created between the can interior and the surface of the coating material which is outside of the communicating passages connecting with the coating chamber and this is done by drawing a vacuum on the inside of the can and in the chamber. Atmospheric pressure exerting a force on the outside or exposed surfaces of the coating material in the tank then causes the material to rise or flow into the can, completely filling it and covering its inside wall surface.

Atmospheric air is then admitted to the can interior preferably adjacent its top or just above the can and at the same time the vacuum is broken. The liquid coating material within the can immediately drains back into the tank leaving a sufficient portion of it adhering to the desired interior can surface as a thin even coating.

One form of apparatus for performing the steps of the invention is shown in Figs. 1 and 2 of the drawings and comprises a tank 11 having a closed bottom 12 and an open top 13. This constitutes a reservoir for holding a supply of liquid coating material 14. A flanged can *a* to be coated is shown as having both ends open and is supported in the open top of the tank on a central vertical tubular member 17 which may be an integral part of the tank structure.

Tubular member 17 is open at both ends, having its top end flared out in an angular throat wall 18. The upper surface of the throat wall adjacent its outer edge is recessed to provide an annular channel 19 which carries a resilient sealing ring 21. The bottom flanged end of the can rests on this sealing ring when it is in coating position.

The bottom end of the member 17 terminates just above the tank bottom 12 and is immersed in the coating material in the tank reservoir. Vertical holding webs 23 are preferably the connecting elements between the member and the side wall of the tank so that there is free communication between the tank interior and the interior of the member through its lower end.

The interior of the can is employed as a part

of a coating chamber which may be considered to also include the interior of the tubular member 17. To provide such a chamber the lower end of the can is momentarily clamped against the sealing ring 21 by a movable head 25. The interior of this head, the interior of the positioned can and the interior of the tubular member all constitute the coating chamber.

The head 25 is formed with a conical skirt wall 26 which flares out over the top of the clamped can completely covering it. An annular channel 27 is formed in the inside surface of the wall 26 adjacent its outer edge and provides a seat for a resilient sealing ring 28 similar to the ring 21. The upper flanged end of the can is tightly engaged by the ring 28, the head being brought down on the can in any suitable manner. The joints adjacent both ends of the can are thus hermetically closed or sealed for the duration of the clamping period or during the coating operation.

The upper part of the head 25 is hollowed out in a bore 31, the lower end of which communicates with the top of the coating chamber. The lower end of the bore is closed at times by a ball valve 25 which comprises a float ball 32 held captive by pins 33 threadedly secured in the conical wall 26. These pins support the ball when it is in its lower, non-closing position (Fig. 1).

The surrounding upper wall of the bore is internally threaded and holds a two way hand valve 35. One outlet of this valve is threadedly secured to a pipe 36 which provides a connection with a pump or other suitable source of vacuum. The other outlet of the valve connects with a short vent pipe 37 which is open to the atmosphere.

With the can clamped between the sealing rings 21, 27, the valve 35 is first turned to open communication between the vacuum pipe 36 and the interior of the can. The air is thus exhausted from the can interior in any desired degree and in so doing the atmospheric pressure acting on the exposed surface of the coating material in the tank forces this coating material up into the tubular member 17, into the sealed can and on up and into the conical part of the head 25 as shown in Fig. 2.

As the ball 32 floats on the rising liquid it moves up and partially into the end of the bore 31. This action closes off the bore and cuts off the vacuum effect from the coating chamber which at that time is completely filled with coating liquid (Fig. 2).

The valve 35 is now turned to disconnect the head from the vacuum supply and to open communication with the vent pipe 37. Air at atmospheric pressure thereupon rushes into the bore 31 and impinging on the ball 32, opens the coating chamber to atmosphere.

The column of liquid material in the head 25, can 21 and tubular member 17 recedes under the force of gravity and drops back into the tank, the float ball again seating on the pins 33. In this draining of the liquid out of the can a sufficient amount adheres to the interior can surfaces to provide the desired film or thin, even coating for those surfaces.

In Figs. 3 and 4 of the drawings there is disclosed a slightly different form of apparatus which may be used to carry out the method steps of the invention, this form being particularly adapted for use with cans having attached bottom ends. Such an apparatus comprises a tank 51 which corresponds to the tank 11 previously described. Tank 51 has a bottom 52 and an open top 53 and

also functions as a holding reservoir for a coating material 54.

At one end of the tank there is provided a vertical tubular member 56 open at both ends and this member may be an integral part of the tank side wall. The upper end of the tubular member projects above the top of the tank and is formed with an obliquely disposed angular throat wall 57 the upper surface of which is preferably inclined at about 30 degrees from horizontal. The can to be coated is inverted over this throat, the can being provided with a bottom end. The upper surface of the throat wall 57 is grooved in an annular channel 59 which forms a pocket for a resilient sealing ring 61. The positioned can rests on this sealing ring with its open end sealed or closed from atmosphere.

Tubular member 56 extends down into the tank 51 terminating just short of the bottom wall 52 and is immersed in the coating material. There is therefore free communication between the tank interior and the interior of the tubular member and the latter together with the interior of the inverted can functions as a coating chamber during the coating operation.

A vertically disposed cylinder 65 is located on the opposite side and is or may be an integral part of the tank. The upper end of the cylinder extends above the top of the tank and is closed with a cap 66 which is threadedly secured in the top end of the cylinder. The lower end of the cylinder is inside the tank proper, being immersed in the liquid coating material therein. This lower end terminates just short of the tank bottom 52, similarly to the tubular member 56.

The cylinder 65 intermediate its length is formed with an annular web or ledge 67 which has a central aperture or valve seat 68 which is adapted to be closed by a ball valve. This valve comprises a float ball 69 which is held captive below the aperture, pins 71 secured in the web 67 being used for this purpose. This is an identical construction to the ball valve used to close the bore 31 of the apparatus of Figs. 1 and 2.

The web 67 divides the cylinder 65 into two parts, the upper part being utilized as a vacuum chamber 73. The vacuum chamber is connected to any suitable source of vacuum through a two-way valve 74 which is threadedly secured at 75 in a wall of the cylinder. A pipe 76 extending from the valve is a part of the pipe line leading from the source of vacuum. The other outlet of the valve includes a short pipe 77 the lower end of which is open to the atmosphere.

Vacuum chamber 73 is connected with the interior of the can positioned on the sealing ring 61 by a pipe 78. That end of the pipe which extends into the chamber 73 passes through and tightly fits in a hole or aperture 79 formed in the cylinder side wall just above the web 67. The other end of the pipe which extends into the tubular member 56 passes through and tightly fits in a hole or aperture 81 formed in the member just below its skirt 57. This end of the pipe is bent as at 82 into the positioned can terminating just short of the can bottom. This terminal pipe end is at the highest point of the pipe (Fig. 3) and is cut off at an angle to enter the upper corner of the can, this also being the highest section of the can interior.

With a can in position on the sealing ring 61 the valve 74 is first turned to open communication between the pipe 76 and the vacuum chamber 73. Air is exhausted from the chamber, from the pipe 78 and from the interior of the posi-

tioned can *a*. Outside atmosphere surrounding the can only holds it more firmly seated on its resilient ring *61*.

This removal of air from the can and from the vacuum chamber relieves the air pressure on the surface of the coating material within the tubular member *56* and on the surface of the liquid in the lower end of the cylinder *65*. Accordingly the coating material rises at these two places being forced up by the atmospheric pressure acting on the surface of the exposed coating material in the tank.

As the level of liquid in the lower end of the cylinder rises it lifts the float ball *69* which guided by the tapered wall surrounding the aperture *68* closes the latter, thereby stopping any further liquid rise in the cylinder.

The rising liquid in the tubular member *56* flows into the can and completely fills it thus covering all of its interior surfaces this being possible by reason of the high position of the end of the pipe *78* within the can as already explained. Some of the coating material flows back and through the pipe *78* and into the vacuum chamber where it falls down on the ball valve. The valve *74* is then turned and the vacuum pull on the vacuum chamber and on the coating chamber is shut off.

Turning of the valve simultaneously opens communication between the chambers and atmosphere by way of the pipe *77* and air at atmospheric pressure immediately enters into the vacuum chamber and into the pipe *78* and thence into the can. This restores the original balance of pressure, the coating material in the can and in the tubular member *56* dropping back to its original level. This action drains the liquid material out of the can, leaving an even coating on all of the required surfaces.

Lowering of the liquid level in the tubular member *56* is accompanied by a like lowering of the liquid level in the cylinder *65* and the ball *69* floats down with the receding liquid and moves away from the aperture *68*. This opens the aperture and any of the liquid material drawn over into the chamber *73* passes back into the lower part of the cylinder and into the tank.

It is thought that the invention and many of its attendant advantages will be understood from the foregoing description, and it will be apparent that various changes may be made in the steps of the process described and their order of accomplishment without departing from the spirit and scope of the invention or sacrificing all of its material advantages, the process hereinbefore described being merely a preferred embodiment thereof.

I claim:

1. A method of coating cans comprising cover-

ing an open end of a can to create a coating chamber which includes the interior of the can, exhausting air from said coating chamber, raising by atmospheric pressure a liquid coating material from a source of supply to flow into said can and over its interior surfaces automatically cutting off communication between said chamber and the air exhausting source after the former has been filled with the coating material, and restoring the interior of the can to atmospheric pressure to return the excess of coating material to said source of supply leaving the interior can surfaces coated.

2. A method of coating containers comprising closing a container to confine an interior space therein against ingress of atmospheric pressure, then introducing by atmospheric pressure a liquid coating material from a source of supply spaced from said container into said container interior space, and thence withdrawing it, said introduction and withdrawal being effected by means of differences of air pressures between said container interior space and the source of coating material.

3. A method of coating containers comprising creating a difference of pressure between the interior of a container to be coated and a source of liquid coating material normally spaced from and out of contact with said container, so that the coating material is directed by atmospheric pressure onto the interior surfaces of the container.

4. A method of coating containers comprising positioning a container to be coated with its interior spaced from and in communication with a confined liquid coating material, and creating a difference of pressure between the interior of said container and the confined coating material so that said material is directed by atmospheric pressure through said container and in contact with its entire interior surface.

5. A method of coating cans comprising placing a can to be coated in an inverted position over and spaced from a liquid coating material, creating a difference of pressure between the interior of said can and the said coating material so that said material is directed and forced by atmospheric pressure into said can, then draining said material out of the can so as to leave a coating on its entire interior surface.

6. A method of coating cans comprising positioning a can to be coated adjacent and spaced from a body of liquid coating material exposed to atmospheric pressure, drawing a vacuum on the interior of said can so that said coating material is forced by atmospheric pressure therein to cover its interior surface, then breaking said vacuum and thereby removing the excess coating material from said can interior at the same time leaving an adhering coating on the can wall.

JOHN M. HOTHERSALL.
